**CATHODE RAY ELECTROSTATIC PRINTING
OR RECORDING DEVICE**

Richard S. Howell, King of Prussia, Pa., assignor to Burroughs Corporation, Detroit, Mich., a corporation of Michigan

Filed Aug. 31, 1961, Ser. No. 135,368

7 Claims. (Cl. 313—73)

The invention hereinafter described and claimed has to do with electrostatic printing or recording heads, but more particularly to a combined cathode-ray tube and electrostatic printing and recording head, whereby such printing or recording may be initiated by means of the cathode beam of the tube, in the manner described and claimed in the co-pending application of Robert E. Benn entitled "Electron Tube" Serial No. 131,337, filed August 14, 1961, and assigned to the assignee of the present invention.

The electrostatic recording process consists broadly of three steps. The first step comprises establishing, or printing, electrically charged areas on selected portions of the recording medium, which areas are representative of information. The second step consists of developing such charged areas on the recording medium, by making them visible, for example. The third step, which is optional, consists in fixing or rendering such developed areas substantially permanent. In electrostatic process these three steps take place sequentially and at physically separate locations.

In the co-pending application Serial No. 729,847, filed April 21, 1958, entitled "Electrographic Recording Process and Apparatus," by Robert E. Benn and Richard S. Sakauri, which application is assigned to the assignee of the present application, the advantages of positively initiating the establishment of a charged area on a recording medium by creating an electrical discharge between an initiating electrode and a print electrode are set forth. In that co-pending application a separate pulse generating source for each print electrode and each initiating electrode of a matrix print head is required. The simultaneous occurrence or application of print and initiating pulses to corresponding print and initiating electrodes initiate the establishment of a charged area on the recording medium located in a gap between the print and initiating electrodes of the print head and a back electrode.

It is brought out in the above identified Benn et al. application Serial No. 729,847, that great simplification in the printing station in the structure of the print heads and the necessary control and pulse generating circuitry required to print alphanumeric information, for example, results when one type of the electrodes in the matrix print heads, the print electrode, for example, are connected in parallel. Still greater simplification is possible if each row of parallel connected print electrodes is replaced by strip or bar electrode, as described and claimed in the co-pending application Serial No. 734,253, filed May 9, 1958, entitled "Electrographic Recording Apparatus," by Robert E. Benn, Richard S. Howell, and Richard S. Sakauri which application is assigned to the assignee of the present invention.

The present invention has for its primary purpose to provide an electrostatic printing or recording head whereby the teaching of the above mentioned Benn, Howell, and Sakauri co-pending application may be combined in a cathode-ray tube as taught in the above identified co-pending Benn application, that is, by incorporating a dual electrode (initiating and printing) printing or recording means in the envelope structure of such a tube. More particularly it has for its purpose to provide such a dual electrode printing or recording means which is easily, economically and efficiently fabricated.

A particular advantage of a system taught in the above identified co-pending applications is that it is only

2

the initiating or selection electrodes which need to be driven by the cathode-beam of such a tube and since the occurrence of the discharge from an initiating electrode to the adjacent printing or bar electrode which is connected to a suitable printing voltage, automatically brings the two electrodes within a few hundred volts of each other in potential, the voltage excursion of the initiating electrodes as a result of a secondary-emission phenomena is restricted, making the operation of the system less sensitive to the different secondary-emission characteristics of various types.

Briefly, in its broadest aspects, the invention provides an electrostatic printing or recording head comprising a row of aligned pin electrodes and a bar electrode common to each pin and electrically insulated from each other, all sandwiched between and bonded to a pair of electrically insulating, preferably lead-glass rods, with an end of each pin and an edge of the bar exposed on one side, and only the opposite ends of the pin electrode on the opposite side. The head unit, in accordance with another aspect of the invention, is bonded to the envelope of a cathode-ray tube, over an opening therein, whereby the exposed pin and bar electrodes on one side are on the outside of the envelope and only the exposed ends of the pin electrodes on the opposite side are on the inside of the tube, thus to form the targets for the cathode beam during printing or recording.

The invention will be more fully appreciated from the following description of the preferred embodiment thereof taken in conjunction with the accompanying drawings, wherein:

FIG. 1 is a schematic plan view of a cathode ray tube incorporating a pin-bar electrostatic recording head in accordance with the invention;

FIG. 2 is a schematic elevational view of the cathode ray tube as seen in FIG. 1, and showing the head in association with a back electrode and a recording medium;

FIG. 3 is a perspective view of two glass rods used in the construction of the invention;

FIG. 4 is a view similar to FIG. 4 but showing the condition of the two glass rods during fabrication of the print head;

FIG. 5 is a transverse sectional view of the recording head illustrative of its condition prior to final lapping or grinding;

FIG. 6 is a fragmentary elevational view of a recording head in accordance with the invention; and

FIG. 7 is a sectional view of the head shown in FIG. 5 as applied to the faceplate of a cathode ray tube, as seen in FIGS. 1 and 2.

Now with reference to the details of the various figures of the drawings and first to FIGS. 6 and 7, it is seen that in accordance with the preferred form, the invention comprises an aligned row of pin electrodes 10, a bar electrode 12 traversing the ends 14 of the pin electrodes, but electrically insulated therefrom by a thin layer of insulation 16 all bonded together, between and to a pair of electrically insulating rods 18 and 20, preferably of lead-glass, by glass frit 21 thus to form the recording unit 22. The envelope 24 (FIGS. 1 and 2) preferably the faceplate 26, of the cathode ray tube 23 is provided with an opening 30 over which the head 22 is hermetically sealed to the envelope. The cathode ray tube 23 may comprise one of conventional shape in which the envelope 24 is elongated with a narrow neck portion 34 at one end and a flared end portion 36 at its opposite end across which the faceplate 26 is bonded. The narrow neck portion 34 houses a conventional beam producing gun 38 and deflection plates 40 for directing a beam to the pin electrodes. In use, a back electrode 42 (FIG. 2) may be provided slightly spaced from the head to form a gap 44 through which a record medium 46 is threaded.

While the head may be fabricated in other ways, it

is preferred to use the method of applicants co-pending application, Serial No. 135,369 filed concurrently herewith, entitled "Method of Fabrication of Cathode Ray Electrostatic Printing or Recording Devices," wherein the method described is as set forth hereinafter.

Two electrically insulating rods 50 and 52 (FIG. 3) approximately $\frac{1}{4}$ " square by 3" long are provided, and may be cut from flat $\frac{1}{4}$ " thick lead-glass sheet.

As seen in FIG. 4 the rod 50 has wound upon it—using suitable coil winding equipment—a .004" diameter molybdenum wire 54 in evenly spaced helical coils at a pitch of .010", and for approximately 2" along the length of the rod.

The wire is oxidized by any suitable means, such as a gas-oxygen flame, after which the glass frit 21 is applied to the rod in an amount sufficient to cover the winding with a melted layer of the frit. This step can be accomplished in an oven by the procedure outlined in the "Corning Product Information Bulletin" authored by L. C. Liptak, November 21, 1957, or by spreading, as with a thin metal spatula, a thin coating of melted frit to the rod after it has been heated and then heating the frit by a hand-held glass blower's gas-oxygen torch. The temperature should not be allowed to exceed approximately 550° C. which is the softening point of the lead-glass rod.

After cooling, one surface 58 (FIG. 5) of the so prepared rod 50 is ground or lapped upon the winding; positions 60 are just exposed through the frit coating 21, as indicated by the line 62.

The rod 52 is now coated on one side 64 only, with a thin layer of glass frit 66, after which a strip 68 of Nichrome approximately .003" thick by $\frac{1}{16}$ " wide by 3" long which has been properly oxidized is layed on top of the frit along the length of rod 12 with a small length 70 thereon, as seen in FIGS. 1 and 7, extending out past the end of the rod 52 to be used later for connection purposes. The Nichrome strip 68 is layed off center with one of its edges 72 about $\frac{1}{32}$ " from the edge of the rod, and then under heat and moderate pressure to insure flatness, the strip is fused to the frit.

Now as seen in FIG. 5 the two glass rods prepared in accordance with the above steps, are placed together with the exposed surface 58 of the windings 60 facing the exposed surface 74 of the Nichrome strip, and with a strip 76 of .0013" thick ribbon glass between them.

Heat at approximately 550° C. is then applied along with moderate pressure until the frit fuses together and the rods are joined to become a single integral unit.

The unit is then cooled and lapped, preferably on all sides, so as to remove all remaining unwanted parts such as the excess wire winding around the outside of bar 50, and the excess glass as indicated by the heavy broken lines 78 on FIG. 5 thus to produce the finished head, whereby as seen in FIGS. 6 and 7, an edge 80 of the strip 12 and the ends 14 of the remaining wire portions, which we will now call pins 10, as formerly designated, are exposed on one side 84 and only the pin ends 86 on the opposite side 88.

It is desirable that the length of the pins 10 sealed within the unit should be as short as possible in the area over which the bar 12 is in close proximity to the pins, thus to minimize the capacity effect between the pins and the bar. Therefore it is preferred to lap the unit from the front 84 that is, where both the edge 80 of the bar 12 and pin ends 14 will be exposed, until the bar becomes as narrow as possible without weakening the print head structure. Then the inside surface 88 of the unit, or that surface where only pin ends 86 will be exposed to the electron beam, is lapped down until the inside edge 90 of the bar 12 is almost exposed, but not quite, since it is essential that only the pins be struck by the beam.

The finished recording head 22 may be approximately

.040" to .050" thick, and as long as desired, in the present case three inches.

The pin-bar unit as described above can now be sealed onto either a glass faceplate 26 of the cathode-ray tube 28, or even a metal faceplate such as is common in the industry today. In either case the recording unit is sealed over an opening on window 30 in the faceplate, and sealing can be accomplished by the use of well known glass frit techniques, as indicated at 96 in FIG. 7.

While there has been described only a single unitary pin-bar electrode, it is within the scope of the invention to provide a complete matrix of such electrodes, by assembling a plurality of such units, and sealing them together along edges 78 and 99, as indicated by the broken lines 97 in FIG. 6.

What is claimed is:

1. In a cathode ray electrostatic recording device having a non-conductive envelope, means in said envelope for generating and projecting a cathode beam, and a pin-bar electrostatic recording head forming a part of the faceplate of said envelope, the improvement of a said head comprising an aligned row of pin electrodes closely spaced from each other, a bar electrode closely adjacent and traversing ends of said pin electrodes, a pair of electrically non-conductive rod means, electrically non-conductive glass means insulating said pin electrodes from each other and from said bar electrode and sandwiching said electrodes between said rods and simultaneously bonding said pin and bar electrodes to each other and to said rods as an integral unit with one end of said pin electrodes and an edge of said bar electrode exposed on the exterior of said envelope in position to effect recording on a record medium, and the opposite pin ends only exposed on the interior of said envelope for impingement by said cathode beam, said electrically non-conductive glass means including a strip of glass of uniform thickness in contact with and between the row of pin electrodes and the bar electrode and establishing a predetermined spacing therebetween.
2. In a cathode ray tube for use in electrostatic recording and having an electrically non-conductive envelope, means in said envelope for generating and projecting a cathode beam, and an electrostatic recording head forming a part of the faceplate of said envelope, the improvement of a said head comprising a pair of electrically non-conductive elongated rods each having at least one flat side along its length, a plurality of pin electrodes, electrically non-conductive glass means bonding said pin electrodes in a line spaced from each other on the flat surface of one of said rods, a bar electrode, non-conductive glass means bonding said bar electrode to the flat surface of the second of said rods, electrically non-conductive glass spacer means insulatingly bonding said rods together as a recording head unit and establishing by contact said pin electrodes and said bar electrode in closely adjacent relationship and sandwiched between said pair of rods with one end of said pin electrodes and an edge of said bar electrode exposed on the exterior of said envelope in position to effect recording on a record medium, and the opposite pin ends only exposed on the interior of said envelope for impingement by said cathode beam.
3. A construction according to claim 2 wherein said pair of rods are of lead-glass, said glass means bonding said pin and bar electrodes to said pair of rods is glass frit, and said non-conductive glass spacer means bonding said rods together as a unit is a thin sheet of glass of uniform thickness fused to a portion of said frit.
4. A construction according to claim 1 and further comprising a plurality of such head units similarly bonded to said envelope.
5. A construction according to claim 4 wherein said plurality of units are bonded to each other to form a matrix of pin-bar electrodes.
6. An electrostatic recording head unit comprising an

aligned row of pin electrodes, a bar electrode closely adjacent and traversing adjacent ends of said pin electrodes, a pair of electrically non-conductive rod means, electrically non-conductive glass means insulating said pin electrodes from each other and from said bar electrode and sandwiching said electrodes between said rods and simultaneously bonding said pin and bar electrodes to each other and to said rods as an integral unit with one end of said pin electrodes and an edge of said bar electrode exposed on one side of said unit, and the opposite pin ends only exposed on the opposite side of said unit, said bar electrode extending from the sandwich parallel to and beyond one end of said rods to provide a connection, and said electrically non-conductive glass insulating means including a planar strip of glass of uniform thick-
15

ness in contact with and between the row of pin electrodes and the bar electrode, and establishing a uniform predetermined spacing therebetween.

7. A construction according to claim 6 and further including a plurality of said head units bonded together to form a matrix of pin-bar electrodes.
